CLAIM

The ornamental design for a food vacuum device, as shown and described.

DESCRIPTION

FIG. 1 is a bottom perspective view of a food vacuum device according to the present invention;

FIG. 2 is a rear perspective view of the food vacuum device of FIG. 1;

FIG. 3 is a front perspective view of the food vacuum device of FIG. 1;

FIG. 4 is a top view of the food vacuum device of FIG. 1; FIG. 5 is a bottom view of the food vacuum device of FIG. 1;

FIG. 6 is a front view of the food vacuum device of FIG. 1; FIG. 7 is a back view of the food vacuum device of FIG. 1; and, FIG. 8 is a side view of the food vacuum device of FIG. 1.
